(57) **ABSTRACT**

An arcuate display device, including an arcuate display surface, a plurality of display units, an image source, and a controller, is provided. The display units are configured on the arcuate display surface in an array manner, and each of the display units includes a plurality of pixels. The controller is configured to receive a plurality of pixel signals from the image source to generate a plurality of frame signals respectively corresponding to the display units. Each of the frame signals includes the pixel signals, a plurality of first dummy signals, and a plurality of second dummy signals, in which the pixel signals respectively correspond to the pixels. A sum of an amount of the pixel signals, an amount of the first dummy signals, and an amount of the second dummy signals in each of the frame signals is same. A driving method of the arcuate display device is also provided.

CROSS-REFERENCE TO RELATED APPLICATION

This application claims the priority benefit of Taiwan application serial no. 111115702, filed on Apr. 25, 2022. The entirety of the above-mentioned patent application is hereby incorporated by reference herein and made a part of this specification.

BACKGROUND

Technical Field

The present disclosure relates to a non-planar display device and a driving method thereof, in particular to an arcuate display device and a driving method thereof.

Description of Related Art

With an increasing development of technology industries, displays have been widely used in daily life. By splicing a plurality of display units (light panels) on an arcuate surface, an arcuate display device can provide an experience different from a flat display and is often used in large-scale exhibition activities.

However, since a display surface of the arcuate display device is non-planar, taking a spherical display device as an example, amounts of pixels possessed by display units at north and south ends are smaller than those possessed by display units at an equator. When an image source controls the display units of different latitudes by a driving device with a same circuit layout design as a flat display device, discontinuous images may occur at splicing areas of the adjacent light panels.

SUMMARY

The present disclosure provides an arcuate display device and a driving method thereof, in which images at splicing areas of the arcuate display device are continuous.

According to an embodiment of the present disclosure, an arcuate display device is provided, which includes an arcuate display surface, a plurality of display units, a virtual axis, an image source, and at least one controller. The display units are configured on the arcuate display surface in an array manner, and each of the display units includes a plurality of display rows, and each of the display rows includes a plurality of pixels. The virtual axis is located on the arcuate display surface, in which the display units are respectively configured on two sides of the virtual axis, and the display rows are configured parallel to the virtual axis. The image source is configured to provide a plurality of pixel signals. The at least one controller is electrically connected between the display units and the image source. The controller is configured to receive the pixel signals and generate a plurality of frame signals respectively corresponding to the display units by using a frame signal generator of the controller, in which each of the frame signals includes the pixel signals, a plurality of first dummy signals and a plurality of second dummy signals, and the pixel signals respectively correspond to the pixels. A sum of an amount of the pixel signals, an amount of the first dummy signals, and an amount of the second dummy signals in each of the frame signals is same.

According to an embodiment of the present disclosure, a driving method of an arcuate display device is provided for driving the arcuate display device. The arcuate display device includes a plurality of display units, an image source and at least one controller. The at least one controller is electrically connected between the display units and the image source. The driving method of the arcuate display device includes the following. The image source provides a plurality of pixel signals. The at least one controller receives the pixel signals, and a plurality of frame signals respectively corresponding to the display units are generated using a frame signal generator of the at least one controller. Each of the frame signals includes the pixel signals, a plurality of first dummy signals and a plurality of second dummy signals. A sum of an amount of the pixel signals, an amount of the first dummy signals, and an amount of the second dummy signals in each of the frame signals is same.

Based on the above, the driving method of the arcuate display device provided by the embodiment of the present disclosure inserts the dummy signals into the frame signals, so that the sum of the amounts of the pixel signals, the amounts of the first dummy signals and the amounts of the second dummy signals in each of the frame signals is the same. Therefore, the display units which possess different amounts can be controlled using the frame signal generator and a driving device with the same circuit layout design, so there will be no discontinuous images at the splicing areas.

In order to make the above-mentioned features and advantages of the present disclosure more obvious and easier to understand, embodiments will be given and described in detail hereinafter with reference to the accompanying drawings.

BRIEF DESCRIPTION OF THE DRAWING

FIG. 1A is a schematic diagram of an arcuate display device according to an embodiment of the present disclosure.

FIG. 1B is a schematic diagram of an arcuate display screen according to an embodiment of the present disclosure.

FIG. 1C is a schematic flat expansion view of the arcuate display screen shown in FIG. 1B.

FIG. 2A is an enlarged view of a plurality of display units shown in FIG. 1C.

FIG. 2B is a schematic diagram of frame signals corresponding to the display units shown in FIG. 2A.

DESCRIPTION OF THE EMBODIMENTS

Referring to FIGS. 1A and 1B, FIG. 1A illustrates a schematic diagram of an arcuate display device according to an embodiment of the present disclosure, and FIG. 1B illustrates a schematic diagram of an arcuate display screen according to an embodiment of the present disclosure. An arcuate display device 100 includes an image source 101, a controller 102 and an arcuate display screen, in which the arcuate display screen includes an arcuate display surface 100S, a virtual axis 1 and a display module 103. The display module 103 includes a plurality of display units 11, 12, 13, 14, 15, 16, 17, 18, 19, 10, 21, 22, 23, 24, 25, 26.

The image source 101 is configured to provide a plurality of pixel signals PSi. The controller 102 is electrically connected between the display module 103 and the image source 101 and receives the pixel signals PSi to control the display units 11, 12, 13, 14, 15, 16, 17, 18, 19, 10, 21, 22, 23, 24, 25, 26. For convenience of description, only one

controller **102** is illustrated in FIG. 1A, which is electrically connected to the display module **103**. But the present disclosure is not limited hereto. In other embodiments of the present disclosure, the arcuate display device **100** may include a plurality of controllers **102** to respectively control the display units **11, 12, 13, 14, 15, 16, 17, 18, 19, 10, 21, 22, 23, 24, 25, 26**. For example, one controller controls a plurality of the display units **11, 12, 13**, one controller controls a plurality of the display units **14, 15, 16**, one controller controls a plurality of the display units **17, 18, 19, 10**, one controller controls a plurality of the display units **21, 22, 23**, and another controller controls a plurality of the display units **24, 25, 26**.

The display units are configured on the arcuate display surface **100S** in an array manner. The virtual axis **1** is located on the arcuate display surface **100S**, and the display units **11, 12, 13, 14, 15, 16, 17, 18, 19, 10, 21, 22, 23, 24, 25, 26** are respectively configured on two sides of the virtual axis **1**. In the embodiment, the virtual axis **1** can be regarded as an equator of the arcuate display screen, and the display units **11, 12, 13, 14, 15, 16, 17, 18, 19, 10, 21, 22, 23, 24, 25, 26** are respectively configured on the arcuate display screen at different latitudes.

Referring to FIG. 1B and FIG. 1C, FIG. 1C is a schematic flat expansion view of the arcuate display screen shown in FIG. 1B. In FIG. 1C, each display unit **11, 12, 13, 14, 15, 16, 17, 18, 19, 10, 21, 22, 23, 24, 25, 26** has a trapezoidal shape. A plurality of the display units **11** are arranged at positions with same minimum distance as a virtual axis **1**. A plurality of the display units **12** are arranged at positions with same minimum distance as the virtual axis **1**. The minimum distance between each display unit **12** and the virtual axis **1** is greater than the minimum distance between each display unit **11** and the virtual axis **1**, and so on. Likewise, a plurality of the display units **21** are arranged at positions with same minimum distance as the virtual axis **1**. A plurality of the display units **22** are arranged at positions with same minimum distance as the virtual axis **1**. The minimum distance between each display unit **22** and the virtual axis **1** is greater than the minimum distance between each display unit **21** and the virtual axis **1**, and so on.

Referring to FIG. 1C and FIG. 2A, FIG. 2A illustrates an enlarged view of the nine display units within a dotted frame in FIG. 1C. The nine display units are respectively three display units **10**, three display units **19** and three display units **18**, and the nine display units are electrically connected to an image source **101** by a same controller **102**. In addition, each of the display units **10, 19** and **18** includes a plurality of display rows **DRi** (the display rows **DRi-1, DRi, DRi+1, and DRi+2** as shown in FIG. 2A, hereinafter collectively referred to as the display rows **DRi** for convenience of description), and each of the display rows **DRi** includes a plurality of pixels **Pi**. Each of the display rows **DRi** is configured parallel to the virtual axis **1**.

As shown in FIG. 2A, the display row **DRi** closer to the virtual axis **1** includes more pixels **Pi**. That is, the display unit closer to the virtual axis **1** includes more pixels **Pi**. Display units having a same distance from the virtual axis **1** have a same amount of the pixels **Pi**. Specifically, in FIG. 2A, the three display units **10** have a same amount of the pixels **Pi**, the three display units **19** have a same amount of the pixels **Pi**, and the three display units **18** have a same amount of the pixels **Pi**. On the other hand, the amount of the pixels **Pi** included in the display units **10** is smaller than the amount of the pixels **Pi** included in the display units **19**, and

the amount of the pixels **Pi** included in the display units **19** is smaller than the amount of the pixels **Pi** included in the display units **18**.

It should be noted that since FIG. 1C is the schematic flat expansion view of the arcuate display screen shown in FIG. 1B, and FIG. 2A is the enlarged view of the nine display units shown in FIG. 1C, although pixels **Pi+1** and **Pi+2** are not illustrated as adjacent to each other in FIG. 2A, the two pixels **Pi+1** and **Pi+2** are substantially adjacent in FIG. 1B and are respectively located on two sides of a splice line between two adjacent display units **10**. Likewise, although pixels **Pi+4** and **Pi+5** are not illustrated as adjacent to each other in FIG. 2A, the two pixels **Pi+4** and **Pi+5** are substantially adjacent in FIG. 1B and are respectively located on two sides of a splice line between two adjacent display units **10**. The adjacent relationship between the pixels of the different display units is not limited to the display row **DRi-1** shown in FIG. 2A, but also applies to other display rows **DRi, DRi+1** and **DRi+2**, etc., which will not be described here.

Referring back to FIG. 1A, the controller **102** includes a preprocessor **1021**, a frame signal generator **1022** and a driver **1023**. The preprocessor **1021** is arranged to temporarily store and preprocess the pixel signals **PSi** from the image source **101**. The frame signal generator **1022** is arranged to generate a plurality of frame signals **FSi**, and each of the frame signals **FSi** corresponds to one display unit. The driver **1023** is electrically connected between the frame signal generator **1022** and the display module **103** and drives the corresponding display unit in the display module **103** according to each of the frame signals **FSi**.

Referring to FIG. 2A and FIG. 2B, FIG. 2B illustrates nine frame signals **FSi** (the nine frame signals **FSi-1, FSi, FSi+1, etc.**, as shown in FIG. 2B, hereinafter collectively referred to as the frame signals **FSi** for convenience of description) respectively corresponding to the nine display units of display units **10**, display units **19** and display units **18** shown in FIG. 2A. As shown in FIG. 2B, each of the frame signals **FSi** is a two-dimensional array signal and includes a plurality of pixel signals **PSi** (the pixel signals **PSi-1, PSi, PSi+1, PSi+2, PSi+3, PSi+4, PSi+5, PSi+6, and PSi+7** as shown in FIG. 2B, hereinafter collectively referred to as the pixel signals **PSi** for convenience of description). Moreover, each of the frame signals **FSi** also inserts a plurality of first dummy signals **D1i** (the first dummy signals **D1i-1, D1i, D1i+1** as shown in FIG. 2B, hereinafter collectively referred to as the first dummy signals **D1i** for convenience of description), and a plurality of second dummy signals **D2i** (the second dummy signals **D2i-1, D2i, D2i+1** as shown in FIG. 2B, hereinafter collectively referred to as the second dummy signals **D2i** for convenience of description), and the pixel signals **PSi** are located between the first dummy signals **D1i** and the second dummy signals **D2i**.

As shown in FIG. 2A and FIG. 2B, an amount of rows of the frame signal **FSi-1** is the same as an amount of rows of the corresponding display units **10** (5 rows is shown as an example, but the present disclosure is not limited hereto), and an amount of the pixel signals **PSi** possessed by the frame signal **FSi-1** is the same as the amount of the pixels **Pi** possessed by the corresponding display units **10**, and corresponding patterns are formed in FIG. 2A and FIG. 2B respectively. Similarly, an amount of rows of the frame signal **FSi** is the same as an amount of rows of the corresponding display units **19**, and an amount of the pixel signals **PSi** possessed by the frame signal **FSi** is the same as the amount of the pixels **Pi** possessed by the corresponding display units **19**, and corresponding patterns are formed in

FIG. 2A and FIG. 2B respectively. An amount of rows of the frame signal FS_{i+1} is the same as an amount of rows of the corresponding display units 18, and an amount of the pixel signals PS_i possessed by the frame signal FS_{i+1} is the same as the amount of the pixels Pi of possessed by the corresponding display units 18, and corresponding patterns are formed in FIG. 2A and FIG. 2B respectively.

Furthermore, although the amount of the pixel signals PS_i of the frame signal FS_{i-1}, the amount of the pixel signals PS_i of the frame signal FS_i, and the amount of pixel signals PS_i of the frame signal FS_{i+1} are different, a sum of the amount of the pixel signals PS_i, an amount of the first dummy signals D_{1i}, and an amount of the second dummy signals D_{2i} in the frame signals FS_{i-1}, FS_i, and FS_{i+1} is the same. That is, although the amount of the pixels Pi possessed by the display units 10, the amount of the pixels Pi possessed by the display unit 19, and the amount of the pixels Pi possessed by the display unit 18 are different, by the method of inserting the first dummy signals D_{1i} and the second dummy signals D_{2i} into each frame signals FS_i, the total amount of the signals in the frame signals FS_{i-1}, FS_i, and FS_{i+1} is the same, so that the display units 10, 19 and 18 can be driven using the frame signals generated by a same frame signal generator 1022. In other embodiments of the present disclosure, the three display units 10, 19 and 18 can be driven using a different frame signal generator 1022 with a same circuit layout design. Moreover, although the amount of the pixels Pi possessed by the display unit 10, the amount of the pixels Pi possessed by the display unit 19, and the amount of the pixels Pi possessed by the display unit 18 are different, the three display units 10, 19, and 18 can also be driven using a same driver 1023. Specifically, by inserting the first dummy signals D_{1i} and the second dummy signals D_{2i}, the display units 10, 19, and 18 possess different amounts of pixels when located at different latitudes on the arcuate display screen and can be driven using the frame signal generator and the driver of the same circuit layout design, and there is no need to design frame signal generators and drivers with different circuit layout designs for the display units at different latitudes.

Furthermore, in each of the frame signals FS_i, the amount of the first dummy signals D_{1i} and the amount of the second dummy signals D_{2i} are the same, and are arranged symmetrically relative to the pixel signals PS_i. As shown in FIG. 2B, in the embodiment, each of the frame signals FS_i is also a two-dimensional rectangular array as frame signals of a flat display. Therefore, the display units 10, 19, 18 can be driven using a frame signal generator of the flat display. Specifically, by inserting the first dummy signals D_{1i} and the second dummy signals D_{2i}, the display units 10, 19, and 18 possess a trapezoidal shape when located at different latitudes on the arcuate display screen, and can be driven using the frame signal generator and the driver of the flat display suitable for trapezoidal shapes.

In addition, for the display row DR_{i-1} shown in FIG. 2A and the pixel signals PS_i shown in FIG. 2B corresponding to the row, since the continuous pixel signals PS_{i-1}, PS_i, PS_{i+1}, PS_{i+2}, PS_{i+3}, PS_{i+4}, PS_{i+5}, PS_{i+6}, PS_{i+7} from the image source 101 are grouped into a first group of pixel signals as shown in FIG. 2B (composed of the pixel signals PS_{i-1}, PS_i, PS_{i+1}), a second group of pixel signals (composed of the pixel signals PS_{i+2}, PS_{i+3}, and PS_{i+4}) and a third group of pixel signals (composed of the pixel signals PS_{i+5}, PS_{i+6}, PS_{i+7}), and the first dummy signals D_{1i} and the second dummy signals D_{2i} are inserted between the first group of pixel signals and the second group of pixel signals and between the second group of pixel signals and the third

group of pixel signals, so that each of the pixels Pi can receive correct pixel signals PS_i (as shown in FIG. 2A and FIG. 2B, the pixel signals PS_{i-1}, PS_i, PS_{i+1}, PS_{i+2}, PS_{i+3}, PS_{i+4}, PS_{i+5}, PS_{i+6}, PS_{i+7} respectively correspond to pixels Pi-1, Pi, Pi+1, Pi+2, Pi+3, Pi+4, Pi+5, Pi+6, Pi+7). Therefore, substantially the pixels Pi-1, Pi, Pi+1, Pi+2, Pi+3, Pi+4, Pi+5, Pi+6, Pi+7 configured adjacently receive the continuous pixel signals PS_{i-1}, PS_i, PS_{i+1}, PS_{i+2}, PS_{i+3}, PS_{i+4}, PS_{i+5}, PS_{i+6}, PS_{i+7}, and even if the pixel Pi+1 and the pixel Pi+2 respectively belong to the different display units, images displayed by the pixel Pi+1 and the pixel Pi+2 are continuous.

Similar to how the display row DR_{i-1} display the continuous images, since a pattern formed by the pixel signals PS_i in each of the frame signals FS_i shown in FIG. 2A corresponds to a pattern formed by the pixels Pi in the corresponding display units in FIG. 2B (the patterns are the same), the images at the splicing areas between the nine display units of display units 10, 19, and 18 in FIG. 2A are all continuous.

More broadly, by inserting an appropriate amount of the first dummy signals D_{1i} and the second dummy signals D_{2i}, each of the display units 11, 12, 13, 14, 15, 16, 17, 18, 19, 10, 21, 22, 23, 24, 25, 26 of the arcuate display device 100 can be driven using the different frame signal generator with the same circuit layout design, or can be driven using the same frame signal generator, and the images at the splicing areas between the display units are all continuous. For example, a lower amount of the first dummy signals D_{1i} and the second dummy signals D_{2i} are inserted into the display units 11 and 21, and a higher amount of the first dummy signals D_{1i} and the second dummy signals D_{2i} are inserted into the display units 16 and 26, so that a total amount of the signals in each of the frame signals, corresponding to the display units 11, 21 or the display units 16, 26, is the same. In this case, the display units 11, 21, 16 and 26 can be driven using the different frame signal generator with the same circuit layout design. By analogy, the display units 11, 12, 13, 14, 15, 16, 17, 18, 19, 10, 21, 22, 23, 24, 25, 26 of the arcuate display device 100 can be driven using the different frame signal generator with the same circuit layout design.

Referring to FIG. 1A, FIG. 1B, and FIG. 2B, a driving method of the arcuate display device is provided for driving the arcuate display device 100 according to an embodiment of the present disclosure. The driving method of the arcuate display device includes: providing the pixel signals PS_i from the image source 101; receiving the pixel signals PS_i using the controller 102; generating the frame signals FS_i respectively corresponding to the display units 11, 12, 13, 14, 15, 16, 17, 18, 19, 10, 21, 22, 23, 24, 25, and 26 using the frame signal generator 1022 of the controller 102 the, in which the first dummy signals D_{1i} and the second dummy signals D_{2i} are inserted between the pixel signals PS_i; and driving the corresponding display units 11, 12, 13, 14, 15, 16, 17, 18, 19, 10, 21, 22, 23, 24, 25, or 26 according to the frame signals FS_i using the driver 1023. Each of the frame signals FS_i includes the pixel signals PS_i, the first dummy signals D_{1i} and the second dummy signals D_{2i}, and a sum of the amount of the pixel signals PS_i, the amount of the first dummy signals D_{1i}, and the amount of the second dummy signals D_{2i} in each of the frame signals is the same FS_i.

To sum up, the driving method of the arcuate display device provided by an embodiment of the present disclosure inserts the dummy signals into the frame signals, so that the sum of the amount of the pixel signals, the amount of the first dummy signals, and the amount of the second dummy signals in each of the frame signals is the same. Therefore,

display units which possess different amounts can be controlled using the frame signal generator and a driving device with the same circuit layout design, so there will be no discontinuous images at the splicing areas.

What is claimed is:

1. An arcuate display device, comprising:

an arcuate display surface;

a plurality of display units, configured on the arcuate display surface in an array manner, wherein each of the display units comprises a plurality of display rows, and each of the display rows comprises a plurality of pixels; a virtual axis, located on the arcuate display surface, wherein the display units are respectively configured on two sides of the virtual axis, and the display rows are configured parallel to the virtual axis;

an image source, configured to provide a plurality of pixel signals; and

at least one controller, electrically connected between the display units and the image source, and configured to receive the pixel signals and generate a plurality of frame signals respectively corresponding to the display units using a frame signal generator of the at least one controller, wherein each of the frame signals comprises the pixel signals, a plurality of first dummy signals, and a plurality of second dummy signals, and the pixel signals respectively correspond to the pixels, wherein a sum of an amount of the pixel signals, an amount of the first dummy signals, and an amount of the second dummy signals in each of the frame signals is same.

2. The arcuate display device according to claim 1, wherein in each of the frame signals, the amount of the first dummy signals is same as the amount of the second dummy signals.

3. The arcuate display device according to claim 1, wherein the amount of the pixel signals of each of the frame signals is same as an amount of the pixels in the corresponding display unit.

4. The arcuate display device according to claim 1, wherein the display units having a same distance from the virtual axis have a same amount of the pixels.

5. The arcuate display device according to claim 1, wherein the at least one controller further comprises a driver electrically connected between the frame signal generator and the display units, and the driver drives the corresponding display units according to the frame signals.

6. The arcuate display device according to claim 1, wherein each of the frame signals is a two-dimensional array

signal formed by the pixel signals, the first dummy signals, and the second dummy signals, and the pixel signals are located between the first dummy signals and the second dummy signals.

5. 7. The arcuate display device according to claim 6, wherein an amount of rows of the two-dimensional array signal is same as an amount of rows of the display rows of the corresponding display unit.

8. A driving method of an arcuate display device for driving the arcuate display device, wherein the arcuate display device comprises a plurality of display units, an image source, and at least one controller, and the at least one controller is electrically connected between the display units and the image source, the driving method of the arcuate display device comprising:

providing a plurality of pixel signals by the image source; receiving the pixel signals by the at least one controller; and

generating a plurality of frame signals respectively corresponding to the display units using a frame signal generator of the at least one controller,

wherein each of the frame signals comprises the pixel signals, a plurality of first dummy signals, and a plurality of second dummy signals, and a sum of an amount of the pixel signals, an amount of the first dummy signals, and an amount of the second dummy signals in each of the frame signals is same.

9. The driving method of the arcuate display device according to claim 8, further comprising:

driving the corresponding display units by a driver of the at least one controller according to the frame signals, wherein the driver is electrically connected between the frame signal generator and the display units.

10. The driving method of the arcuate display device according to claim 8, further comprising:

inserting the first dummy signals and the second dummy signals between the pixel signals.

11. The driving method of the arcuate display device according to claim 8, wherein each of the frame signals is a two-dimensional array signal formed by the pixel signals, the first dummy signals, and the second dummy signals, and the pixel signals are located between the first dummy signals and the second dummy signals.

12. The driving method of the arcuate display device according to claim 11, wherein the first dummy signals and the second dummy signals are arranged symmetrically relative to the pixel signals.

* * * * *
